BUILD-UP UNIT FOR CABINET STRUCTURES

Richard W. Sitler, St. Charles, Ill., assignor to Aurora Equipment Company, Aurora, Ill., a corporation of Illinois

Application April 17, 1957, Serial No. 653,409

1 Claim. (Cl. 312—195)

This invention relates generally to cabinet structures and more particularly to a build-up unit for attachment to a cabinet.

Where it is desirable to provide a continuous row of desk-like units it is here contemplated that rather than utilizing a series of adjacent independent desk-like units, that a basic dependent build-up unit be utilized of the type whereby the dependent build-up unit may be connected to a cabinet to afford a desk-unit in a continuous row of such desk-units. By utilizing a build-up unit the buyer's cost may be substantially reduced without substantial sacrifice in the utility or construction of the desk-like units.

Accordingly, it is an object of this invention to provide a new and improved dependent build-up unit.

Still another object of this invention is to provide a dependent build-up unit having an economical construction with the result that the buyer's cost may be substantially reduced.

Still another object of this invention is to provide a continuous row of dependent build-up units each of which depends on adjacent units for support to provide a series of desk-like units.

According to the general features of this invention there is provided in a cabinet structure including a basic cabinet unit for providing a desk type cabinet unit, the improvement of a build-up unit for assembly with the basic cabinet unit, the build-up unit being U-shaped including spaced upper and lower superimposed legs with the upper leg comprising a counter and with the lower leg comprising a rigidifying shelf, an upright cabinet portion connecting the legs together at the bight of the U, the upper leg having opposite end portions one of which is carried on top of and fastened to the cabinet portion and the other of the end portions being adapted to be fastened to the basic cabinet unit, the lower leg having terminal portions one of which is fastened in abutting engagement against the cabinet portion and the other terminal portion adapted for abutting engagement and attachment to the basic cabinet unit below the upper leg.

According to other features of this invention the upper leg portion in the above cabinet structure is substantially elongated in length relative to the lower leg for overlying retained disposition on top of a portion of the basic cabinet structure to provide a desk-type cabinet unit.

Other objects and features of the present invention will more fully become apparent in view of the following detailed description taken in conjunction with the accompanying sheets of drawings illustrating therein several embodiments and in which:

Figure 1 is an isometric view of a dependent build-up unit;

Figure 2 is an enlarged cross-sectional view taken substantially on the line II—II of Fig. 1 looking in the direction indicated by the arrows only with certain detail added in Figure 2;

Figure 3 is an isometric view of an extended desk-type

2

cabinet unit having my dependent build-up unit in assembly therewith;

Figure 4 is an isometric view of a modified desk-type cabinet unit having the build-up unit of Fig. 1 in assembly therewith;

Figure 5 is an isometric view similar to Fig. 4 only showing the basic build-up unit in assembly with a single door type cabinet unit; and

Figure 6 is a front elevation of a desk-like cabinet unit with a modified form of my build-up unit in assembly therewith.

The reference numeral 10 indicates generally a dependent build-up unit for assembly with a cabinet or other structures such as a desk type cabinet unit. The unit 10 especially lends itself to use in the provision of a continuous row of desk type cabinet units. The build-up unit is preferably made from fabricated metal so as to provide a sturdy durable structure. The build-up unit 10 is U-shaped in configuration and includes spaced upper and lower super-imposed legs 11 and 12 with the upper leg comprising a counter and with the lower leg comprising a rigidifying shelf. Disposed between the legs 11 and 12 is an upright locker cabinet portion or locker unit 13 which is in assembly with the legs at the bight of the U.

The lower leg 11 is preferably generally L-shaped in having a pair of leg portions 14 and 15 which are at right angles to one another. The leg portions 14 and 15 are defined at the periphery by peripheral edge portions 16 all of which are turned away at right angles from the leg portions 14 and 15 to reinforce the leg 11 (Figure 1). At opposite ends of the leg 11, the peripheral edge portions 16 are provided with slots 17.

The upper leg 12 has a main counter portion 18 which terminates at the forward end thereof in a downwardly turned skirt portion 19. To reinforce the skirt portion 19 its lowermost peripheral edge portion 20 is turned away at right angles therefrom. Disposed at the rearward area of the counter portion 18 is an upwardly turned back panel portion 21.

At the left hand side of the leg 20, a channel 22 is fastened to the counter portion 18 by means of fasteners 23.

Associated with the legs 11 and 12 is the cabinet structure 13 which in the illustrated form is shown provided with a hinge mounted swingable locker door assembly 24 including a latch 25 to open and close the door.

In the assembly of the leg 11 with the cabinet 13 fasteners 26 are utilized for fastening the longitudinally opposite peripheral flange portions 16 to side wall 27 of the cabinet structure 13 at one end and to a supporting structure such as that shown in Figure 3. It is in this manner that the longitudinally spaced peripheral flange portions 16 of the legs 14 and 15 are maintained in abutting assembly with the side wall 27.

In the assembly of upper leg 12, a portion of the upper leg is carried in overlying assembly upon the top of the cabinet structure 13. To this end, fasteners 28 are utilized to secure the counter portion 18 to wall portion 29 of the cabinet structure 13 to maintain the leg 12 in assembly therewith.

With the completion of the construction and assembly of the dependent build-up unit 10, it will be noted the legs 11 and 12 each extend the same distance away from the cabinet structure 13.

Shown in Fig. 3 is an application of my dependent build-up unit with a desk-type cabinet unit 30. The unit 30 has laterally spaced cabinets 31 and 32 with the cabinets 31 and 32 each provided with a series of drawers 33 and 34. Connecting the cabinets 31 and 32 are upper and lower legs 35—35' which have substantially the same

cross-sectional configuration as the legs 11 and 12. When the build-up unit 10 is in assembly with the desk-type cabinet unit 30 a continuous flat working area is provided by the legs 12 and 35. The build-up unit 10 is assembled with the desk-type unit 30 by suitable means such as by extending fasteners through the slots 17 and 22' of the legs 11 and 12 and fastening them in place with respect to the side wall of the cabinet 32.

Shown in Fig. 4 is another application of my basic dependent build-up unit 10 with a cabinet unit 36. The build-up unit 10 may be fastened to the cabinet unit 36 in the same manner as was set forth in connection with the assembly of the unit 10 with the desk-type cabinet unit 30. In this case, the cabinet unit 36 has an upper counter structure 37 in assembly with the cabinet 36 which counter structure 37 has substantially the same cross-section configuration as the upper leg 12. It is in this manner that a continuous unbroken substantially level work area is provided.

In Fig. 5 is shown another application of my dependent build-up unit with a locker cabinet unit 38. The unit 38 is identical with the unit 36 except that the cabinet unit 36 in Fig. 4 is provided with a series of drawers as opposed to the single locker door on the cabinet unit 38 in Fig. 5. The relationship of the build-up unit 10 with respect to the cabinet units 36 and 38 is otherwise the same.

Shown in Fig. 6 is a modified dependent build-up unit 40 which is constructed substantially the same as the unit 10 with the exception that upper leg 12' is substantially elongated in length relative to lower leg 11' and that the channel 22, shown in Figure 1, has been eliminated from assembly with the leg 12'. In this instance, the build-up unit 13 is assembled with a door type cabinet structure 41 to provide a desk type cabinet structure 42. The extended leg 12' is in overlying abutting disposition on top of the cabinet unit 41. Fasteners of the type shown at 28 in Fig. 2 may be utilized to secure the extended leg 12' to the upper wall of the cabinet 41. The lower leg 11' may be fastened to the cabinet unit 41 in the same manner as is the leg 11 in build-up unit 10. To provide additional storage space, a stacked series of connected drawers 42 are suitably fastened to the underside to the upper leg 12'.

It will be noted the desk type cabinet units 30 and 43 are substantially the same only one has drawer type cabinets and the other has door or locker type cabinets.

In view of the foregoing it will now be appreciated how a continuous row of desk-like units of low cost may

be provided by utilizing a series of basic dependent build-up units in assembly with one another. A buyer's cost may be substantially reduced by the use of dependent build-up units without a substantial sacrifice in the utility of the desk-like units. It will also be appreciated the build-up units may be used in the provision of independent desk-like units if desired.

It will be understood that modifications and variations may be effected without departing from the scope of the novel concepts of the present invention.

I claim as my invention:

In a bench structure, a desk type bench unit comprising a basic bench unit and a build-up unit in assembly together, said build-up unit comprised of a suitable bendable metal such as steel and the like and being U-shaped including spaced upper and lower superimposed prefabricated legs with the upper leg comprising a metal counter and with the lower leg comprising a metal rigidifying shelf, an upright cabinet portion connecting said legs together at the bight of the U, said upper leg having opposite end portions with one end portion being carried on top of said cabinet portion, fastening means securing said one end portion in assembly on top of said cabinet portion, and the other of said end portions being fastened to the basic cabinet unit, said lower leg having angled terminal portions and fasteners, one of the angled terminal portions having its fasteners extending transversely therethrough securing the angled terminal portion against said cabinet portion, and the other angled terminal portion having its fasteners extending transversely therethrough securing the angled terminal portion to the basic cabinet unit below said upper leg, said legs each including a generally horizontal flat portion with oppositely extending integral vertical flange portions with the rear flange portion extending upwardly and the front flange portion extending downwardly, said front portion of said upper leg comprising a skirt overlapping and concealing the junction of said leg with the top of said cabinet portion as well as serving as part of the front of the cabinet portion.
